Garrison Smith and Henry Brown, of Philadelphia, Penn.
Assors to

March and Fisher, of Lawrenceville, Penn.

Letters Patent No. 1803. Dated July 7, 1863.

The schedule referred to in these Letter Patent and making part of the same.

To all whom it may concern:

Be it known that we, Garrison Smith and Henry Brown, of Philadelphia, County of Philadelphia, State of Pennsylvania, have invented or produced a new and original design for Stove Plates; and they do hereby declare the accompanying drawing with the following explanation of the same, to form a full, clear and exact description of the said Design.

In reference to the accompanying drawing.

Fig. 1 is a view of the large oven door of a cooking stove.

Fig. 2, a view of the small door of the oven.

Fig. 3, The door for the fire place when wood is used as fuel, and

Fig. 4, a view of one of the front doors of the fire place.

The large oven door, Fig. 1, is edged with a plain moulding and has a central ornament composed of a large convex boss, surrounded by a row of small convex bosses, and between this central ornament and the border of the plate, the latter is ornamented with the scrolls illustrated in the drawing.

The other doors Figs. 2, 3, and 4, have ornaments of a character similar to those on the large door, these ornaments being too distinctly shown in the drawing to need description.

We claim the ornamental figures and forms represented in and by the accompanying drawing, the whole forming an ornamental design for the doors of a cooking stove.

In testimony whereof we have signed our names to this specification in the presence of two subscribing witnesses.
